ATTORNEY

UNITED STATES PATENT OFFICE.

SILAS M. FORD, OF ST. PAUL, MINNESOTA; CLARA P. FORD, EXECUTRIX OF SAID
SILAS M. FORD, DECEASED, ASSIGNOR TO CLARA P. FORD, OF ST. PAUL, MINNE-
SOTA.

LATH BOARD.

Application filed November 23, 1920, Serial No. 426,020. Renewed July 24, 1925.

To all whom it may concern:

Be it known that I, SILAS M. FORD, a citizen of the United States and a resident of St. Paul, in the county of Ramsey and State of Minnesota, have invented certain new and useful Improvements in a Lath Board, of which the following is a specification.

One object of my invention is to provide in a lath board formed of flexible sheeting, improved means for retaining the said sheeting in place.

Another object of my invention is to provide in a lath board formed of flexible sheeting and having alternating lath like faces and intermediate depressions, means for positively supporting the faces thereof from collapsing.

With these and incidental objects in view, the invention consists of certain novel features of construction and combination of parts, the essential elements of which are hereinafter described with reference to the drawings which accompany and form a part of this specification.

In the drawing, Fig. 1 is a perspective view of a fragment of my improved lath board; Fig. 2 is a section taken on the line 2—2, Fig. 1; and Fig. 3 is a similar view of a modified form of my invention.

The waterproof paper 1 is formed as shown into dove-tail shaped plaits thereby producing alternate lathlike faces 2 and 3 respectively.

These lathlike faces are connected by webs 4 and the flat wire 5 pierces the webs 4 as shown more clearly in Fig. 2 and this wire is of such a width as to completely fill the space between the inner surface 6 of the lathlike face on one side of the sheet and the inner surface 7 of a similar lathlike face on the opposite side of the sheet so that all of the lathlike faces of the sheet of lath board so formed are positively supported and prevented from collapsing by this wire.

In my Patent Number 1,156,866, October 12, 1915, for lath board, I showed reinforced strips 6, which were intended to reinforce the form lath board shown in that patent and which is of the same general character as the lathboard shown herein.

When, however, I began to manufacture this lath board on a commercial scale I

found it advantageous to market the lath board in flat sheets rather than in rolls.

When the lath board as produced under the said patent was made in flat units and these units piled one on top of the other for shipment, I discovered the weight of the sheets superimposed, one on the other would flatten out the corrugations so the resulting board received by the customer would be shorter than when manufactured, the thickness of the lath board would be less and the key space between the lathlike faces would be shortened and the reinforcing wire would project out beyond each end of a sheet of lath board. In cases where the board was not flattened in shipment it would flatten down when laying plaster over it so the board was yielding instead of rigid.

To obviate this trouble I devised the means herein described and while at first glance it seems a small matter to use a flat wire of a certain width, I find it a very important factor in the production of lath board to use a wire of such width that the lathlike faces are positively positioned and supported as there can be no variation in shipment of the thickness of the lath board, key spaces or over-all length of the sheet.

In the construction shown in Fig. 3, I obtain approximately the same result as shown in Fig. 2; in this case, however, the reinforcing wire 8 may be either round or square and is bent at 9, 10, 11 and 12 so a wire of light weight may be used to give support to the lathlike face in the same general way as does my preferred construction heretofore described.

In either of the embodiments shown I prefer the plait form shown although this same reinforcing means may, of course, be embodied in any form of corrugated sheet.

While I have described my invention and illustrated it in two particular designs, I do not wish it understood that I limit myself to these constructions, as it is evident that the application of the inventions may be varied in many ways within the scope of the following claims.

Claims:

1. In a lath board formed of a sheet of flexible material the combination of a plurality of lathlike faces alternately disposed

on both sides of the lath board so formed, webs connecting said alternating faces and reinforcing means passing through said webs and lying in surface contact with the inside surface of said lathlike faces.

2. In a lath board the combination of a sheet of suitable material corrugated into a dove tail sheet formation having alternating

lathlike faces and depressions on each side thereof, webs connecting said alternating lathlike faces, and a flat wire piercing said webs and of such a width and so positioned that said wire lies against and supports the inside surface of each of said lathlike faces. 10

SILAS M. FORD.
